UNITED STATES PATENT OFFICE.

EMIL M. KRAMER, OF CISSNAPARK, ILLINOIS.

GRAIN-CONVEYER.

SPECIFICATION forming part of Letters Patent No. 769,947, dated September 13, 1904.

Application filed May 18, 1903. Serial No. 157,742. (No model.)

To all whom it may concern:

Be it known that I, EMIL M. KRAMER, a citizen of the United States, residing at Cissnapark, in the county of Iroquois and State of Illinois, have invented certain new and useful Improvements in Grain-Conveyers; and I do hereby declare that the following is a full, clear, and exact description of the invention, which will enable others skilled in the art to 10 which it appertains to make and use the same.

This invention relates to conveyers for handling grain and other substances, such as ore and the like.

The primary object of my invention is to 15 provide means for releasing a track-carried conveyer for permitting it to automatically change its position on its track, so that grain may be delivered into different receptacles.

Another object is to provide an automatically-adjustable conveyer for depositing grain into a series of bins or receivers.

Still another object is to provide a peculiar mechanism for accomplishing the above purposes.

25 In the drawings herewith presented, Figure 1 is a plan view of a portion of my conveyer, showing the gearing for operating it. Fig. 2 is a side elevation of a portion of the conveyer and means for locking it in a desired position. Fig. 3 is a side elevation of the conveyer, showing the track on which it is carried. Fig. 4 is a perspective view of one end of the conveyer, showing a swiveled delivery-spout therefor. Fig. 5 is a perspective view of a portion of the conveyer and its track, showing the locking means above mentioned.

A indicates the conveyer, on which are carrying-wheels B, adapted to run upon the track 40 C, the latter being supported from the roof of the granary or other building containing bins or receivers to be filled with grain or other material, such as has been described and shown in a previous application filed by 45 me on the 22d day of December, 1902, and bearing the serial number 136,286.

The driving mechanism herein shown and described is also shown in the above application, but the novel features of this present

device will appear as the description proceeds.

At D the conveyer is provided with a bottom over which runs a smooth belt E by means of carrier-rollers F at each end of the said bottom. The lower stretch of the belt 55 is driven by means of three rollers G H I, said belt passing over the roller G, under roller H, and over roller I, as shown in Fig. 3. These are journaled on top of a frame J, located on the top of the bins, and a supplementary frame K is located adjacent to the frame J and carries a shaft L, parallel with the conveyer. On said shaft are two beveled gears L', loose on said shaft and meshing with a similar gear M, secured on the shaft of the 65 roller H. Also upon the shaft L is a shifting-sleeve N, having a projection O at each end to enter depressions at P in the hubs of the loose gears L'. Said sleeve is adapted to revolve with the shaft, this being accomplished 70 by a key Q, secured in the shaft and upon which the sleeve slides. On the shaft L is a sprocket-wheel R for transmitting motion to said shaft from any source of power. I provide a forked lever S, which is pivoted on 75 the frame K and is used to shift the sleeve N from one gear to the other. It will be seen that motion imparted to the shaft L in one direction will transmit motion to the roller H in one direction or the other, depending upon which gear L' is engaged by the shifting-sleeve N. This has been described in the application above referred to and will need no further attention here.

I now desire to direct attention to the means 85 for locking the conveyer in any desired position upon the track C described. At one side of the conveyer and attached thereto is a U-shaped bracket U, having a vertical spring-bolt V, adapted to enter sockets in the under surface of the track C, (indicated at W.) Said spring-bolt carries a fixed collar 1, against which a spring 2 is adapted to bear, the other end of such spring bearing upon the lower horizontal limb of the bracket U. This normally keeps the bolt raised and in engagement 90 with one of the sockets W of the track, so that the conveyer is prevented from moving. The

spring-bolt is provided with an eye 3 at its lower end, with which engages a U-shaped arm or crank 4, having its bearing in a bracket 5, secured to the conveyer. A rope is attached 5 to said arm 4, by which the spring-bolt may be withdrawn from the socket W. Said arm or crank 4 is merely used to carry the pull-cord 6, used therewith, out beyond the frame J, as indicated in Fig. 1, so that the bolt may 10 be operated without interference by said frame. Evidently other means may be employed to withdraw the spring-bolt, or the frame J may be arranged in such a way that the bracket 5 and said arm 4 may be dispensed 15 with. It is necessary when the bins or receivers are of large size and cover considerable territory to have the distributing-conveyer therefor shift on its track in both directions, so that any bin may be reached for 20 deposit of grain thereinto. The rollers G H I, being driven from the shaft L through the gears described, will drive the belt E in one direction or the other, so that the grain deposited on said belt from the elevator (not shown) will be delivered from one end or the 25 other of the conveyer.

When it is desired to shift the conveyer while the rollers are moving, it is only necessary to pull down the rope 6 and withdraw 30 the spring-bolt from engagement with the track, and the conveyer will be moved by the belt E in the direction in which the upper stretch of said belt is traveling, as will be understood. By holding said bolt down the conveyer will move to the desired position, where 35 it may be arrested from further progress by permitting the bolt to contact with the track, where it will enter the first socket W that passes above it. If it is desired to shift the 40 conveyer in the other direction, a simple reversal of the movement of the belt through the medium of the shifting-sleeve N will accomplish it.

On each end of the conveyer is a swiveled 45 spout A', slotted at 7. A pin 8 is passed through the slot and secured in the fixed portion of the conveyer and holds the said spout in place and allows said spout to be swung in any direction, so that the grain may be deposited at either 50 side of the conveyer into one or the other of the bins T, as shown in Fig. 1.

I am aware that there are conveyers of the 55 nature of mine adjustable for the purposes stated herein, but to my knowledge such devices have not been supplied with the means for locking the conveyer at the desired place

after it has been moved by the belt by the means I employ, and

Therefore I claim--

1. The combination of the horizontal adjustable conveyer A, the track C at the sides of the conveyer, the wheels B on the conveyer for running upon the track, the rollers F at each end of the conveyer, the belt E running on the same, the rollers G, H, I journaled beneath the 60 conveyer through which the belt passes and driven therefrom, the vertical spring-bolt V on the conveyer for engaging the track, the pull-cord for withdrawing the spring-bolt from engagement with the track and being 65 operated from below, the rollers shifting the conveyer by means of the belt E along the track when the spring-bolt is withdrawn from the track said conveyer being free to move until the bolt is again in engagement with the 70 track as set forth.

2. The combination of the conveyer A, the track C, the wheels B on the conveyer for traversing the track, the rollers F in the conveyer, the belt E thereon, the rollers G, H, I beneath 80 the conveyer, the belt running over one, beneath the second and over the third substantially as shown and for the purposes set forth, the bracket U secured to the conveyer, the spring-bolt V carried therein, the spring 2 for holding the bolt in engagement with the track, there being sockets in the under side of the track into which said bolt is adapted to seat and a pull-cord 6 for withdrawing the bolt to permit the belt and driving-rollers to shift the 85 conveyer on its track for the purposes set forth.

3. The combination of the conveyer A, wheels B thereon, the track C, rollers F in the conveyer, the belt E thereon, rollers G, H, I, 95 for driving the belt, the bracket U secured to the conveyer, the spring-bolt V carried thereby, the spring 2 for normally keeping the bolt in engagement with the track, there being sockets in the track for receiving the bolt, the arm 4 in engagement with the bolt V, the bracket 5 for carrying the arm 4 and the pull-cord 6 attached to the arm for withdrawing the spring-bolt substantially as set forth and described.

In testimony whereof I affix my signature in presence of two witnesses.

EMIL M. KRAMER.
